UNITED STATES PATENT OFFICE.

MINNIE SWEDBURG, OF OMAHA, NEBRASKA.

DESIGN FOR A BASKET.

No. 37,569.

Specification for Design.

Patented Oct. 3, 1905.

Application filed July 8, 1905. Serial No. 268,883. Term of patent 3½ years.

To all whom it may concern:

Be it known that I, MINNIE SWEDBURG, a citizen of the United States, residing at Omaha, in the county of Douglas and State of Nebraska, have invented a new, original, and ornamental Design for Baskets, of which the following is a specification, reference being had to the accompanying drawing, forming a part hereof.

The figure is a perspective view of a basket, to showing my new design.

I claim—

The ornamental design for a basket, as shown.

MINNIE SWEDBURG.
